UNITED STATES PATENT OFFICE

2,455,276

DROP BOTTOM MINE CAR LATCH

Robert A. Shields, Bloomsburg, Pa., assignor to
 American Car and Foundry Company, New
 York, N. Y., a corporation of New Jersey

Application September 20, 1946, Serial No. 698,307

11 Claims. (Cl. 105—308)

1

This invention relates to latches in general but in particular to latches intended to hold closed or release the bottom doors of mine cars.

Drop bottom mine cars are at present controlled by single part rotating hooks carried either by the car end wall or by the car end sill. Frequently it has been impossible to apply such latch hooks to cars which were intended to operate in low vein coal mines since the necessary unlatching motion could not be obtained with the parts located within the clearances permitted. It is an object, therefore, of the present invention to provide a latch for drop bottom mine cars which will permit the mounting of the same on cars of extremely low height.

Another object of the invention is the provision of a multi-part latch for drop bottom cars in which the door engaging hook will rapidly move out of engagement with the door lug.

A still further object of the invention is the provision of a multi-part latch for drop bottom mine cars which may be automatically retained in the released position until tripped by the closing door.

A yet further object of the invention is the provision of a latch for drop bottom mine cars with the part so arranged as to decrease the wear on the door lug and hook.

These and other objects of the invention will be apparent to persons skilled in the art from a study of the following description and accompanying drawings, in which

Fig. 1 is a rear end view of a car with parts broken away to better disclose the latch construction;

Fig. 2 is a sectional view taken substantially on line 2—2 of Fig. 1;

Fig. 3 is an enlarged detailed view of the latch in released position, and

Fig. 4 is a sectional view taken substantially on line 4—4 of Fig. 3.

Referring now to the drawings in detail, it will be seen that the latch has been applied to a mine car of more or less conventional form having wheels W supporting the car by means of axles which support the sills 2 to which are attached the side walls 4 and end walls 6. The side sills, as is customary, are joined together by an end sill construction 8 carrying bumpers 10 and draft attachments 12. The space between the end sills and side sills is closed by one or more drop bottom doors 14 with at least one of these doors having a door lug 16 attached to the rear or free edge thereof.

As clearly shown the door lug is adapted to rest 55 particularly desirable where mechanical loading

2

on the ledge 18 of the swinging latch hook 20. This hook is pivotally mounted as at 22 to the downturned end of an angular shaped operating handle 24, which handle is pivoted to the car at 26. As shown in the drawings the pivot 26 is carried by the end sheet 6 and by a bracket 28. It will be obvious, of course, that this pivot mounting for the operating handle can be carried by the end sill if it is so desired. In order to make a strong operating handle it has been built up by two angles placed with their flanges touching and welded together to give a box section handle, as clearly shown in Fig. 2. The short flanges of each angle are cut away as at 30 in order to permit the ready mounting of pivot pin 22 and to permit the swinging of the upper end of latch hook 20. The upper end of the latch hook is shown as located between the long flanges of the operating handle and has pivoted thereto as at 32 a strap 34, the opposite end of which is pivoted as at 36 to the car structure. The torsion spring 38 has one end anchored to the car structure and the other end bearing on the link 34 tending to force the same in a clockwise direction as viewed in Figs. 1 and 3. In order to prevent any longitudinal shift of the hook 20 a lug 40 is formed thereon and adapted to rub on a wear plate 42 attached to the back or inner surface of the end sill structure as best shown in Fig. 2.

As shown in Fig. 1 the pivot pins 26 and 22 and the bearing point of door lug 16 on hook ledge 18 are substantially in the same vertical plane when the door is latched, thus relieving the link 34 and operating handle 24 of any strain. When, however, the operating handle is moved to a released position, that is, lifted from the position of Fig. 1 to the position of Fig. 3, the lower end of the operating handle will move causing the pivot 22 to swing in a counter-clockwise direction. Due to the anchoring of the upper end of the swinging latch hook to the car structure by link 34, the latch will rotate also in a counter-clockwise direction relative to the car and to the operating handle, but since pivot 32 is above pivot 22 the lower end of the latch hook will swing at a much greater rate than does pivot pin 22. Thus it will be seen that by properly proportioning the parts it will be possible to cause the hook to swing through a distance substantially equal to the lift of the operating handle. In this way the pivotal mount 26 for the operating handle may be brought much closer to the door lug 16 than has previously been possible. This will permit of the use of drop bottom cars in extremely low vein mines. This is

is used in these mines, thereby requiring a latch end which is lower than the sides of the car.

The latch parts as proportioned are so arranged that when the operating handle is lifted to the full released position as shown in Fig. 3 the pivot 32 will be slightly below the line joining the centers of pivot pins 36 and 22. This locking toggle action of the links coupled with torsion spring 38 will hold the operating handle and latch hook in the position shown in Fig. 3. When, however, the door 14 is brought to closed position the lug 16 thereof will strike the projecting portion 50 of the latch hook, thereby breaking the toggle lock between the hook and link 34 and permitting the hook to quickly swing into engagement with the door lug. This type of latch assembly will eliminate considerable of the wear in the hook previously caused by the scrubbing action between the lug and the hook of the conventional car when the doors are closing. Also, due to the self-locking feature of the parts in raised position, this assembly can be very readily used with automatic arm locking arrangements of the type shown in Patent 2,376,826 granted May 22, 1945. With the type of latch assembly shown the special trackside equipment for the operating arm described in this patent can be eliminated.

While the latch construction has been described more or less in detail, it will be obvious that the assembly may be readily modified and attached to other parts of the car than those shown and all such modifications and rearrangements are contemplated as will fall within the scope of the following claims defining my invention.

What is claimed is:

1. A drop bottom mine car having a car body and a dumping door, a latch operator pivoted to the car body, a latch hook pivoted to said latch operator and swingable relative to said car body and latch operator, means carried by said dumping door and engageable by said latch hook to retain the dumping door in closed position, and means connected to said latch hook and to said car to cause swinging of said latch hook relative to the car body at a rate greater than the rate of swinging of the latch operator relative to the car body.

2. A drop bottom mine car having a car body and a dumping door, a latch operator pivoted to the car body, a latch hook pivoted to said latch operator and swingable relative to said car body and latch operator, means carried by said dumping door and engageable by said latch hook to retain the dumping door in closed position, and means connected to said latch hook and car body to cause swinging of the latch hook relative to the latch operator during swinging of the latch operator whereby said latch hook is moved out of engagement with said first named means.

3. A drop bottom mine car having a car body and a dumping door, a latch operator pivoted to the car body, a latch hook pivoted to said latch operator and swingable relative to said car body and latch operator, a lug connected to said dumping door in position to be engaged by said latch hook to retain the dumping door in closed position, and a link pivotally connected to said latch hook and car body, the pivotal connection between said link and latch hook being located to one side of the latch hook pivot to the latch operator.

4. A drop bottom mine car having a car body and a dumping door, a latch operator pivoted to the car body, a latch hook pivoted to said latch

operator and swingable relative to said car body and latch operator, a lug connected to said dumping door in position to be engaged by said latch hook to retain the dumping door in closed position, and a link pivotally connected to said latch hook and car body, the pivotal connection to said latch hook being normally located between the pivotal mounts for said latch operator and latch hook.

5. A drop bottom mine car having a car body and a dumping door, a latch operator pivoted to the car body, a latch hook pivoted to said latch operator and swingable relative to said car body and latch operator, a lug connected to said dumping door in position to be engaged by said latch hook to retain the dumping door in closed position, and a link pivotally connected to said latch hook and car body, said pivotal connections of the link and hook being so positioned as to comprise a self-locking toggle holding the latch hook in released position.

6. A drop bottom mine car including a car body and a dumping door, a latch operator, a first pivot pin connecting an intermediate portion of said latch operator to the car body, a latch hook, a second pivot pin connecting an intermediate portion of said latch hook to said latch operator adjacent an end thereof, a link, a third pivot pin connecting one end of said link to said latch hook, a fourth pivot pin connecting the other end of said link to said car body, and a lug carried by said dumping door in position to be engaged by said latch hook to retain the door in closed position.

7. A drop bottom mine car including a car body and a dumping door, a latch operator, a first pivot pin connecting an intermediate portion of said latch operator to the car body, a latch hook, a second pivot pin connecting an intermediate portion of said latch hook to said latch operator adjacent an end thereof, a link, a third pivot pin connecting one end of said link to said latch hook, a fourth pivot pin connecting the other end of said link to said car body, and a lug carried by said dumping door in position to be engaged by said latch hook to retain the door in closed position, said first and second pivot pins and lug being located substantially in a common plane when said dumping door is being retained in closed position.

8. A drop bottom mine car including a car body and a dumping door, a latch operator, a first pivot pin connecting an intermediate portion of said latch operator to the car body, a latch hook, a second pivot pin connecting an intermediate portion of said latch hook to said latch operator adjacent an end thereof, a link, a third pivot pin connecting one end of said link to said latch hook, a fourth pivot pin connecting the other end of said link to said car body, and a lug carried by said dumping door in position to be engaged by said latch hook to retain the door in closed position, said third pivot pin being located slightly below a line connecting the axes of said second and fourth pivot pins when the dumping door is in open position to thereby form a self-locking toggle retaining the latch operator in raised position.

9. A drop bottom mine car including a car body and a dumping door, a latch operator, a first pivot pin connecting an intermediate portion of said latch operator to the car body, a latch hook, a second pivot pin connecting an intermediate portion of said latch hook to said latch operator adjacent an end thereof, a link, a third pivot pin connecting one end

of said link to said latch hook, a fourth pivot pin connecting the other end of said link to said car body, and a lug carried by said dumping door in position to be engaged by said latch hook to retain the door in closed position, said third pivot pin being located slightly below a line connecting the axes of said second and fourth pivot pins when the dumping door is in open position to thereby form a self-locking toggle retaining the latch operator in raised position, and means on said latch hook engageable by said lug upon closing of the dumping door whereby said third pivot is moved above the line connecting the axes of said second and fourth pivot pins to thereby break the self-locking toggle permitting the latch hook to engage said lug.

10. A drop bottom mine car including a car body and a dumping door, a latch operator pivoted to said body, a latch hook pivoted to said latch operator and swingable relative thereto, means on said door engageable by said latch hook to retain said dumping door in closed position, and means pivotally connected to said latch hook and to said car to control the swinging movements of said latch hook.

11. A drop bottom mine car including a car body and a dumping door, a latch operator pivoted to said body, a lug on the dumping door, a latch hook pivoted to said latch operator and swingable into engagement with said lug to retain the dumping door in closed position, and a link connected to said latch hook and to said car body for causing a rate of swinging of said latch hook greater than that of the latch operator.
